(57) **CLAIM**

The ornamental design for a flying disc, as shown and described.

DESCRIPTION

FIG. 1 is a front, bottom and right-side perspective view of the flying disc showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, rear and left-side perspective view thereof;

FIG. 9 is an enlarged view, of circled portion 9, of FIG. 3, thereof;

FIG. 10 is an enlarged view, of circled portion 10, of FIG. 4, thereof; and,

FIG. 11 is an enlarged view, of circled portion 11, of FIG. 8, thereof.

The broken lines throughout the drawing figures depict portions of the flying disc that form no part of the claimed design.

The dot-dash broken lines depict the boundaries of the FIGS. 3, 4, and 8-11 enlargement that form no part of the claimed design.

1 Claim, 11 Drawing Sheets
